UNITED STATES PATENT OFFICE.

FREDERICK M. OSGOOD, OF MANCHESTER, NEW HAMPSHIRE.

GARMENT-HANGER.

SPECIFICATION forming part of Letters Patent No. 678,073, dated July 9, 1901.

Application filed February 21, 1901. Serial No. 48,267. (No model.)

To all whom it may concern:

Be it known that I, FREDERICK M. OSGOOD, a citizen of the United States, residing at Manchester, county of Hillsboro, State of New Hampshire, have invented an Improvement in Garment-Hangers, of which the following description, in connection with the accompanying drawings, is a specification, like figures on the drawings representing like parts.

This invention relates to garment-hangers; and it is the object of the invention to provide a collapsible or folding garment-hanger which when extended is adapted to support an entire suit—that is, both the trousers and coat and vest of a gentleman's suit or the skirt and jacket of a lady's suit.

To this end my invention comprises a suitable head, to which is swiveled, preferably by a ball-and-socket joint, a supporting-hook, the said head having pivoted thereto, on opposite sides thereof, wings, which when in operative position are adapted to sustain a coat or similar garment. The head has also pivotally connected thereto and depending therefrom a pair of garment-supporting arms which have attached to their lower ends spring-clamps, the said clamps being adapted to grip the waistband of a pair of trousers or a skirt, as the case may be. The arms are connected together by a toggle-joint, the ends of the toggle-levers extending beyond the arms and being pivotally connected to the wings by a suitable link. With this construction when the toggle-levers of the toggle-joint are brought into alinement and locked in such position the garment-supporting arms are spread to such a width that the spring-clamps at the end thereof are in proper position to grip and support the waistband of the trousers or skirt. The link connection between the extended ends of the toggle-joint and the wings operates to support the wings in their extended position, whereby a coat or jacket may be sustained by the wings in the usual manner. When not in use, the toggle-levers may be collapsed and the wings and arms folded to occupy a minimum space.

In the drawings, Figure 1 shows my garment-hanger extended. Fig. 2 illustrates the garment-hanger folded or collapsed. Fig. 3 is a section on the line α , Fig. 1. Fig. 4 is an enlarged view of one of the clamps on the

garment-supporting arms. Fig. 5 is a plan view of one of the wings; and Fig. 6 is a section on the line γ , Fig. 1.

55

The head to which the wings and garment-supporting arms are pivoted is designated by 3, and it has the hook 8 swiveled thereto, the said head being preferably made from a blank of sheet metal, which is bent to form the depending side flanges 4, between which the wings and arms, hereinafter described, are preferably pivoted. Each side flange has the concave half-round socket 5 therein, the said sockets being opposite each other, as seen in Fig. 3, and forming a seat for the spherical enlargement 6 on the end of the shank 7 of the supporting-hook 8, the shank 7 of the hook passing through a suitable aperture 9 in the top of the head, as best seen in Fig. 3. 70 This ball-and-socket connection between the hook and the head enables the hook to be freely turned about a vertical axis, and by placing the half-round socket 5 some distance below the aperture 9 the hook is braced and held firmly in an upright position. Pivoted to the head, on opposite sides thereof and preferably between the flanges 4, are the wings 9, which form the supporting means for the coat or jacket or similar garment, the said wings being supported upon suitable pivot-pins 12. These wings are preferably made of wire and are of the shape illustrated in Fig. 5, each wing comprising the frame 10 and the cross-piece 11. The head 3 has also 80 pivoted thereto the garment-supporting arms 13, the pivot-points 14 of the same with the head being below the pivot-points 12 of the wings with the head, for purposes hereinafter described, and the said garment-supporting arms are provided at their lower ends with suitable devices for sustaining a pair of trousers or a skirt by the waistband, the said supporting devices being shown in this instance as spring-clamps 15.

95

In order to prevent the jaws of the clamps from injuring the garment held between the same, I preferably provide the said jaws with rubber lips 16, 17, the lip 16 being shown as having a depression therein and the lip 17 having a corresponding projection to fit the depression, thus operating to more firmly hold the garment in place.

The garment-supporting arms 13 are con-

100

- nected by a suitable toggle-joint comprising the toggle-levers 19 20, the said levers being pivoted to the arms 13 intermediate their ends and extending beyond the arms, as at 21 22.
- 5 The extended ends 21 22 of the levers 19 and 20 are pivotally connected to the wings 9 by means of suitable links 23, the said links when the device is extended operating to support the wings 9 in their operative position, 10 as plainly seen in Fig. 1.

To maintain the garment-hanger in its extended or operative position, I have provided a locking mechanism operating to lock the toggle-levers 19 and 20 in alinement, as shown 15 in Fig. 1, and for this purpose the lever 19 is shown as being extended, as at 27, beyond the pivotal point 25 between the same and the lever 20, and a sleeve 26 is carried by the arm 20 and is adapted to be telescoped over the 20 projecting end 27 of said lever 19.

When it is desired to fold or collapse the garment-hanger, it is simply necessary to slide the sleeve 26 to the right, Fig. 1, until the end 27 of the lever 19 becomes free, when the toggle-joint may be buckled and the arms and wings folded into the position shown in Fig. 2.

It will be obvious that other forms of locking mechanism for maintaining the arms of the toggle-levers in alinement may be employed, if desired, the sleeve 26 merely being illustrated as one convenient form of locking device.

It is sometimes desirable to support the trousers from the lower end of the legs instead 35 of from the waistband, and in order to adapt the garment-supporting arms 13 for supporting the trousers from either the waistband or the bottom I make the arms 13 of wire, the lower ends thereof being made flexible, preferably 40 by making a loop 30 therein. With this construction the lower ends of the garment-supporting arms may be bent inwardly, as illustrated in dotted lines in Fig. 1, sufficiently so that the clips 15 are near enough together to 45 allow the same to grip the lower ends of the trousers-legs.

From the above description it will be seen that I have provided a collapsible or folding garment-hanger which is adapted to support 50 an entire suit, the said garment-hanger comprising a head to which is pivotally connected a pair of wings for supporting a coat or similar garment and also a pair of garment-supporting arms having suitable means for supporting a skirt or trousers, and various 55 changes may be made in the structure of the device without departing from the spirit of my invention, and I therefore reserve the right to make such changes as come within 60 the scope of the appended claims.

Having described my invention, what I claim as new, and desire to secure by Letters Patent, is—

1. In a garment-hanger, a head, a pair of 65 wings pivotally connected thereto and adapted to support a coat or like garment, trousers or skirt supporting devices depending from

the head, and pivoted connections between each of said wings and said trousers or skirt supporting device.

70

2. In a garment-hanger, a head, a pair of wings pivotally connected thereto and extending therefrom on opposite sides thereof, a pair of garment-supporting arms depending from said head, and pivotally-connected links uniting 75 each arm with the adjacent wing.

3. In a garment-hanger, a head, a pair of wings pivotally connected thereto on opposite sides thereof, a pair of garment-supporting arms also pivoted to said head and depending 80 therefrom, said arms having means to support a garment, and pivoted connections between said arms and wings, whereby the hanger may be folded when not in use.

4. In a garment-hanger, a head, a pair of 85 garment-supporting arms pivotally connected thereto, a pair of toggle-levers pivoted to said arms intermediate their ends, a pair of wings pivoted to said head, and links connecting said wings and toggle-levers.

90

5. In a garment-hanger, a head, a pair of wings pivotally connected thereto on opposite sides thereof, a pair of garment-supporting arms also pivoted to said head, the pivot-points of said arms with said head being below the pivot-points of 95 said wings with said head, a pair of toggle-levers pivoted together, and pivotally connected to the garment-supporting arms intermediate their ends, each of said toggle-levers extending outward beyond its pivotal point 100 with the garment-supporting arm, links connecting said wings and extended ends of the toggle-levers, and means to lock the toggle-levers in alinement, the construction being such that when the locking means is released the 105 arms and wings of the garment-hanger may be folded together.

6. In a garment-hanger, a head, a supporting-hook swiveled thereto, a pair of wings pivoted to the head, and when in operative position extending in opposite directions, a pair of garment-supporting arms also pivoted to the said head, and said arms and wings being 110 flexibly connected together, whereby the device may be folded when not in use, and means 115 to hold the said arms and wings extended.

7. In a garment-hanger, a head, a supporting-hook having a ball-and-socket connection therewith, a pair of wings pivoted to said head, garment-supporting arms also pivoted 120 to said head, said arms and wings being flexibly connected together, and means to hold said arms and wings in their operative position, the construction being such that when not in use the arms and wings of the hanger 125 may be folded together.

8. In a garment-hanger, a head of substantially inverted-U shape in cross-section, the side walls thereof each having a concave seat, a supporting-hook having a shank extending 130 through an aperture in the top of said head, the end of said shank terminating in a substantially spherical enlargement which is enclosed by said seats, combined with a pair of

garment-supporting arms pivotally connected to said head, and means to hold said arms extended.

9. In a garment-hanger, a head, a pair of yielding arms pivotally connected thereto, said arms having at their lower ends spring-clamps, toggle-levers connecting said arms intermediate their ends, and means to maintain said arms in their operative position.

10. 10. In a garment-hanger, a head, a supporting-hook swiveled thereto, a pair of wings pivotally connected to said head on opposite sides thereof, a pair of garment-supporting arms also pivoted to said head, the lower ends of said arms being flexible and having attached thereto spring-clamps, toggle-levers

pivoted to said arms intermediate their ends, said levers extending beyond the arms, and links connecting the wings with the extended ends of the toggle-levers, and means to maintain said toggle-levers in alinement, the construction being such that when the toggle-levers are buckled the arms and wings may be folded together. 20

In testimony whereof I have signed my name to this specification in the presence of two subscribing witnesses.

FREDERICK M. OSGOOD.
